FLORAL BOUQUET HOLDER OR THE LIKE

Chester Dare and Joseph Schaul, Chicago, Ill.

Application February 26, 1959, Serial No. 54,753

Term of patent 14 years

(Cl. D35—3)

Fig. 1 is a view in perspective of a floral bouquet holder or the like embodying our new design;

Fig. 2 is a front perspective view thereof with the clamps in open position;

Fig. 3 is a front elevational view thereof as shown in Fig. 2;

Fig. 4 is a rear elevational view thereof;

Fig. 5 is a top plan view thereof as shown in Fig. 4;

Fig. 6 is a right side elevational view thereof as shown in Fig. 2; and

Fig. 7 is a view similar to Fig. 3, but with the clamps in the proper position for being packed.

We claim:

The ornamental design for a floral bouquet holder or the like, as shown.
